VISIBLE INDEX

Charles E. Attwood, Chicago, Ill., assignor to
Acme Visible Records, Inc., Chicago, Ill., a corporation of Delaware

Application December 20, 1940, Serial No. 370,940

5 Claims. (Cl. 129—16.7)

This invention relates to visible record systems or filing devices and particularly to improvements in a visible index record card and a holder therefor.

It is an object of this invention to provide a folded or double record card or sheet adapted to be mounted on a generally conventional card holder of the type having a transparent sheath embracing its lower marginal edge, the record card and card holder being provided with novel cooperative engagement means whereby the front leaf of the folded card is adapted to have free swinging movement on a fold line with the rear leaf without detaching the rear leaf from its mounted connection with the card holder.

Other objects relate to details and economy of construction, and arrangement of parts which will be apparent from a consideration of the following specification and drawing, wherein:

Fig. 1 is a face view of a double visible index record card mounted on a card holder illustrating my invention.

Fig. 2 is an enlarged section on the line 2—2 of Fig. 1.

Fig. 3 is a perspective view of my improved double record card.

Fig. 4 is a face view of a generally conventional card holder provided with means for cooperative engagement with the record card illustrated in Fig. 3.

Referring to the drawing, 10 indicates a card holder having a transparent sheath 11 embracing its lower marginal edge. In the illustrations the card is shown to be provided with a weakened hinge line resulting from the perforations 12, and a hanger 13 secured to the upper marginal edge portion of the holder 10. It will be understood, however, that separate hinges, hangers and the like means well known to the art may be utilized for mounting card holders swingably and in overlapping relationship on suitable flanged frames, trays and the like mounting or supporting means.

As illustrated best in Fig. 4, the generally conventional card holder is provided with a plurality of oblique slots 14 adjacent the upper corners of the holder 10 for reception of the upper corners of a mounted record card, the lower marginal edge of the card being received within the sheath 11. For the purpose of the present invention I do not make use of the slots 14, but I provide a longitudinally extending slot 15 adjacent and parallel to the upper marginal edge of the holder 10, in substantial alignment with the

transverse axis or midway between the side edges thereof.

The double or folded index card, best illustrated in Fig. 3, comprises a sheet or card folded or creased on the line 16 to provide a lower leaf 17 and a front leaf 18 of unequal length. The front leaf 18 is sufficiently shorter than the rear leaf 17 in that when the double card is mounted on the card holder 10 with the lower marginal edge of the lower leaf 17 fully inserted within the sheath 11, the lower marginal edge of the front leaf 18 will be clear of the sheath so as to permit it to swing freely on the fold line 16.

In order to securely mount the double card 15 on the holder 10 and yet permit the front leaf 18 to have free swinging movement without disengaging the lower leaf during operative use of the double card, I slit the lower leaf 17 to provide a tongue 19 midway between the side edges of the double card, parallel to the fold line 16 terminating at and opening to the said fold line. This tongue 19 is of somewhat lesser width than the length of slot 15, the slot 15 being spaced from the lower marginal edge of the card 10 a sufficient distance so that when the lower marginal edge of the lower leaf 17 is inserted within the sheath 11, the tongue 19 may be inserted through the slot 15 and to thereby lock the lower leaf 17 adjacent an upper marginal edge portion thereof 30 to the card holder 10 adjacent an upper marginal edge portion of the holder, and thus permitting the front leaf 18 to swing freely about the fold line 16 while permitting the lower leaf 17 to remain securely engaged at all times, and at 35 the same time permitting normal use and access to the lower leaf 17 and both faces of the upper leaf 18.

As previously stated, the oblique slots 14 on the holder 10 are not necessary in my invention, although the provision of a holder 10 with both the slots 14 and the slot 15 permits the holder to be used interchangeably for conventional single card use or for use with my double card by the mere inclusion of the added slot 15.

45 I claim as my invention:

1. A visible index record filing device of the class described comprising a card holder having a sheath embracing a lower marginal edge portion thereof and a record card or sheet doubled to form a rear leaf and a relatively shorter front leaf removably mounted thereon, the lower marginal edge portion of said rear leaf extending within said sheath and the upper marginal edge portion thereof being formed with a centrally positioned tongue extending through a slot formed

in said holder adjacent its upper marginal edge portion and in locking engagement therewith, the said front leaf being adapted to swing freely on its fold relative to said rear leaf.

2. A visible index record filing device of the class described comprising a card holder having a sheath embracing a lower marginal edge portion thereof and a record card or sheet doubled to form a rear leaf and a relatively shorter front leaf removably mounted thereon, the lower marginal edge portion of said rear leaf extending within said sheath and the upper marginal edge portion thereof comprising an upwardly projecting tongue extending through a slot formed in said holder adjacent and parallel to its upper marginal edge portion and in locking engagement therewith, the said front leaf being adapted to swing freely on its fold relative to said rear leaf.

3. A visible index record filing device of the class described comprising a card holder having a sheath embracing a lower marginal edge portion thereof and a record card or sheet doubled to form a rear leaf and a relatively shorter front leaf removably mounted thereon, the lower marginal edge portion of said rear leaf extending within said sheath and the upper marginal edge portion thereof being slotted to provide an upwardly projecting tongue of relatively greater width than length, the said tongue extending through an elongated slot formed in said holder adjacent and parallel to its upper marginal edge portion and in locking engagement therewith, the said front leaf being adapted to swing freely on its fold relative to said rear leaf.

4. A visible index record filing device of the class described comprising a card holder having a sheath embracing a lower marginal edge portion thereof and a record card or sheet doubled to form a rear leaf and a relatively shorter front leaf removably mounted thereon, the lower marginal edge portion of said rear leaf extending within said sheath and the upper marginal edge portion thereof being slotted to provide an upwardly projecting tongue of relatively greater width than length terminating at the line of fold of said card and substantially centered about its vertical axis, the said tongue extending through an elongated slot formed in said holder adjacent and parallel to its upper marginal edge portion and in locking engagement therewith, the said front leaf being adapted to swing freely on its fold relative to said rear leaf.

5. A record card or sheet adapted to be removably mounted on a visible index record card holder having a sheath embracing its lower marginal edge and formed with a slot adjacent and parallel to its upper marginal edge, the said record card comprising sheet material doubled to form a rear leaf and a relatively shorter front leaf, the said rear leaf being slotted adjacent the upper marginal edge thereof to provide an integral upwardly projecting tongue terminating at the line of fold of said leaves, the said tongue being adapted to extend through the said slot in the card holder to engage the rear leaf of the doubled card thereto and to permit the front leaf to swing freely on its fold relative to said rear leaf.

CHARLES E. ATTWOOD.
